UNITED STATES PATENT OFFICE.

WILLIAM McARTHUR, OF TENINO, WASHINGTON.

BURNER.

Application filed December 27, 1920. Serial No. 433,338.

To all whom it may concern:

Be it known that I, WILLIAM McARTHUR, a citizen of the United States, residing at Tenino, in the county of Thurston and State 5 of Washington, have invented a new and useful Burner, of which the following is a specification.

This invention relates to burners designed to use, as a fuel, a mixture of pulverized coal, peat or other fuel dust with alcohol or any other light oil.

One of the objects of the invention is to provide simple and efficient means for effecting a proper mixture of the fuel ingredients before they are directed to the point of consumption, the mixing of the parts being controllable readily.

A further object is to provide apparatus of this character which can be made in various sizes and shapes so as to adapt the same for use with large or small boilers, with stoves, etc.

With the foregoing and other objects in view which will appear as the description 25 proceeds, the invention resides in the combination and arrangement of parts and in the details of construction hereinafter described and claimed, it being understood that, within the scope of what is claimed, 30 changes in the precise embodiment of the invention shown can be made without departing from the spirit of the invention.

In the accompanying drawings the preferred form of the invention has been 35 shown.

In said drawings—

Figure 1 is a view partly in front elevation and partly in section of the burner and the fuel mixing apparatus combined therewith.

Figure 2 is a plan view.

Figure 3 is an enlarged section on line 3—3, Figure 1.

Referring to the figures by characters of 45 reference 1 designates an oil container which can be of any desired configuration. As shown in Figure 2 this container is semi-cylindrical but it will be obvious that the same can be made in the form of three 50 quarters of a cylinder or can be otherwise shaped so as to properly fit upon or against a supporting structure. Arranged within this container is a substantially conical holder 2 for finely comminuted fuel, this 55 holder preferably extending from the top

to the bottom of the container 1 and having its small lower end opening into an outlet tube 3 extending below the bottom of the container 1. The top of the holder 2 can be provided with a removable cover 4 60 and a suitable baffle or spreader 5 can be supported in the lower portion of the holder and spaced from the outlet tube by supporting legs 6.

Extending from the outlet tube 3 is a 65 nipple 7 which opens into the top of a receiving tube 8 arranged under the container 1 and closed at one end but open at its other end. A tapered nozzle 9 extends from the open end of the tube 8 and beyond the 70 wall of the container and is adapted to project through the wall of the stove or other structure to which the fuel is to be supplied. An outlet pipe 10 extends from the bottom of the container 1 into the top 75 of the nozzle 2 and is provided with a valve 11 whereby the flow of oil from the container to the nozzle can be controlled. Opening into the closed end of the tube 8 is a blast pipe 12 which terminates between 80 said end and the nipple 7 and communicates with a tank 13 or the like for supplying air under pressure. If a tank is used as shown a pressure gage 14 may be mounted thereon. A valve 15 is provided 85 for controlling the flow of air through the pipe 12.

A valve 16 is mounted in the tube 3 and by means thereof the discharge of the comminuted material from the holder 2 can be 90 controlled. An oil gage for indicating pressure can be connected to the lower portion of the container 1 as shown at 17. An oil supply pipe 18 opens into the upper portion of the container and has a controlling valve 95 19. A pressure gage 20 is carried by this pipe 18 for indicating air pressure.

In using the apparatus alcohol or other light oil is admitted under air pressure to the container 1 through the pipe 18. The 100 pulverized coal or other combustible material is placed in the holder 2. The valve 15 is opened so that a jet of air will be discharged longitudinally within the receiving tube 8 and across the lower end of the nipple 7 into the nozzle 9. Valves 16 and 11 are then opened desired distances so as to secure the proper mixture of fuel. The dust discharged into the tube 8 will thus be blown into and through the nozzle where it will be 110

mixed with the oil discharged into the nozzle, it being understood that the air blast will break up the oil into a fine spray which will be mixed thoroughly with the fuel.

5 Thus a highly combustible fuel mixture will be delivered from the nozzle.

The baffle 5 serves to prevent the powdered fuel from choking the outlet tube 3.

10 It will be seen that the apparatus is very simple, inexpensive and efficient and can be applied readily to stoves and the like.

What is claimed is:

1. In an apparatus of the class described, a liquid fuel tank, an inverted cone-shaped 15 powdered fuel compartment located in said tank with an aperture in its apex opening through the bottom of the tank, said tank having a fluid outlet spaced from said powdered fuel outlet, a tapered discharge nozzle, valved pipes leading from the outlets of 20 said powdered fuel and liquid fuel compartments to said nozzle and opening thereinto in planes at right angles to the longitudinal axis of the nozzle at points spaced longitudinally from each other, the liquid fuel pipe 25 being located in advance of the powdered fuel pipe, a compressed air supply pipe opening through the larger end of said nozzle in the same direction as the longitudinal 30 axis thereof, said nozzle and air supply pipe

being in longitudinal alinement and supported below the bottom of the tank.

2. In an apparatus of the class described, a liquid fuel tank having an inverted cone-shaped holder arranged therein and extending from the top to the bottom of the tank with its apex provided with an opening extending through said tank bottom, an outlet tube leading from said opening below the bottom of the tank, a removable cover at 40 the upper end of said holder, a nipple leading from said tube, a receiving tube arranged in a plane at right angles to said nipple and through one side wall of which said nipple extends, said receiving tube being open at 45 one end and closed at the other, a tapered nozzle extending from the open end of said tube beyond the wall of the tank, a pipe connecting the tank with said nozzle in advance of the connection of said receiving tube, and 50 a blast pipe opening into the closed end of the receiving tube and terminating between said end and said nipple.

In testimony that I claim the foregoing as my own, I have hereto affixed my signature 55 in the presence of a witness.

WILLIAM McARTHUR.

Witness:

P. C. KIBBE.
